PROTECTING FINGER FOR SHUTTLE HOUSINGS

Thursten Engstrom, Paterson, N. J.

Application May 3, 1933, Serial No. 669,185

6 Claims. (Cl. 139—185)

This invention relates to improvements in shuttle housings of looms in general, and particularly to what is known as "protecting finger," in cooperation with the shuttle speed brake means of such housings.

The employment of abutment devices or "fingers" is well known in the art, however, all such devices possess the great disadvantage of wearing rapidly, due to which wear they very often break 10 during the operation of the loom, requiring immediate stoppage of the machine, which entails costly delay. Aside of these disadvantages, the breaking of the fingers often cause serious injury to the looms.

15 The present invention is designed not only to overcome the aforesaid shortcomings of existing devices, but is intended to simplify and cheapen the production and enhance the usefulness of the so called "protecting fingers". This will be clearer 20 understood from the fact that at the present time the left-hand and right-hand shuttle housings require the employment of left-hand and right-hand protecting fingers, whereas, the present invention obviates the production of left-hand and 25 right-hand fingers, by substituting a universal device of this kind, suitable for employment at either side of the loom; in short, my device is exchangeable at will.

The prime object of my invention, therefore, is 30 to provide a simple, relatively inexpensive, but highly efficient device of this kind, which may be employed at either side of the loom in connection with a shuttle housing and its shuttle speed braking means, and which possesses the great advantage of friction reducing means, which are in 35 themselves exchangeable and adjustable for proper cooperation with the shuttle housing.

The foregoing and still further objects will become more fully apparent from the following description and the accompanying drawing, forming part of my disclosure, which drawing, however, is by no means intended to limit me to the actual construction shown, and in which

45 Figure 1 illustrates a semi-diagrammatical top view of a shuttle housing.

Figure 2 is a partial front elevation thereof.

Figure 3 is a front elevation of my improved device, and

50 Figure 4 is a side elevation thereof, partially in section.

Referring now to the figures, numeral 10 denotes the shuttle housing, provided with a removable frame member 11, which latter possesses lugs 12 and 13, between which are operatively mounted 55 shuttle speed braking means 14, which are nor-

mally induced to press inwards by a spring 15, secured at 16 to frame member 11. Shuttle speed braking means 14 are hinged at 17 and are prevented from leaving frame 11 by a pin 18.

From Figure 2 it will be observed that two 60 spring-propelled members 14 are employed and that their extreme right-hand ends 14' are both engaged by one of the rollers 19 of my improved protecting finger, indicated at 20 in Figures 1 and 2. This protecting finger is adjustably and 65 removably mounted upon a rod 21, shown in Figure 1.

The illustrated construction of a shuttle housing is intended for accommodating either one or 70 two shuttles. The operation of the spring-propelled shuttle speed braking members 14 is about as follows: When a shuttle, marked in broken lines, leaves its housing, spring 15 presses member 14 inwards, keeping it under tension. The moment the shuttle returns, it presses member 75 14 outwards until stopped by pin 18. During the outwards movement of member 14, end 14' come into abutting contact with roller 19 of my finger. Due to its ability of rooving, the wearing off of 80 the roller surface is gradual and uniform.

Figures 1 and 2 illustrate the left-hand portion of a loom, and a similar arrangement is intended for the right-hand portion of a loom, but in reversed position. My protecting finger 20 is also mounted in reversed position, that is, 85 turned 180 degrees from that illustrated in Figures 1 and 2, or in the position shown in Figure 4.

Referring now to Figures 3 and 4, my improved universal finger consists of a bracket portion 22, at the lower end of which is provided an 90 attaching hub 23, from which extends downwardly a boss 24, in which is mounted a set screw 25, adapted to bear against rod 21, forming a part of the loom. At the upper end of bracket portion 22, there is provided a roller housing 26, in 95 which are provided oil holes 27 for lubricating the interior, and thereby rollers 19, which latter are mounted in the housing. These rollers are preferably rotatable upon a short shaft, indicated at 28, which is off-set once at one end, 100 marked 29, while at both ends are provided threaded off-sets 30, engaged by nuts 31. These nuts are secured within outer recesses 32, so as to prevent their projecting beyond the outer surfaces of the roller housing. Adjacent to outer 105 recesses 32 are provided longitudinal, vertical recesses 33, in which the ends of shaft 28 may be adjusted vertically to any desired position.

The arrangement of two rollers in the roller housing 26 and their symmetrical disposition rel- 110

ative to the vertical centre plane of the bracket portion (see Figure 3) facilitates the employment of my device at either left or right-hand ends of the loom. The provision of rollers reduces the 5 wear and tear, to which heretofore used devices of similar nature were unguardedly subjected. Consequently, a break-down of a loom equipped with my finger arrangement (due to a failure of the latter) is quite remote. Due to the fact that 10 my rollers are exchangeable, they may be readily replaced without requiring the scrapping of the entire finger bracket, as is the case in present-day devices. Due to the exchangeability of the fingers, it is possible, when one set of rollers is 15 worn down, to switch the left-hand finger to the right, and the right-hand finger to the left, whereby the formerly unused rollers are brought into operation. The adjustability of the rollers permits their proper setting relative to ends 14' of 20 braking members 14, as is particularly required when double shuttle housings are employed. (See Figure 2.)

For oiling holes 27 there may be substituted a 25 permanently attached lubricating arrangement, not shown, although such is not absolutely necessary. Nevertheless, the lubrication of the roller housing is an essential requirement of this invention, as it reduces friction between the roller shafts and the rollers, and between the rollers 30 and members 14 of the shuttle housing.

The construction shown in the drawing is adapted for use in connection with the greatest proportion of existing looms. It is obvious, however, that changes might become necessary in 35 adapting the principle of my invention to looms of other constructions, and I therefore wish it to be understood that I shall have the right to make such changes and improvements as may be required, due to the application of my device to 40 different types of shuttle housings.

Having thus described my invention, I wish to cover the same as follows.

I claim:

1. The combination with a shuttle housing, including spring-induced, operative shuttle speed braking means, of an exchangeably mounted element adapted to cooperate with the latter, said element comprising an attachable bracket portion and a roller housing portion, the latter symmetrically arranged relative to said bracket portion, a pair of symmetrically disposed rollers mounted in said roller housing and adapted to cooperate with said braking means, said roller housing provided with guide-ways for adjusting 55 the position of said rollers relative to said braking means.

2. The combination with a shuttle housing, including spring-induced, operative shuttle speed braking means, of an exchangeably mounted element adapted to cooperate with the latter, said element comprising an attachable bracket portion and a roller housing portion, the latter symmetrically arranged relative to said bracket portion, a pair of symmetrically disposed rollers mounted in said roller housing and adapted to cooperate with said braking means, said roller housing provided with guide-ways for adjusting the position of said rollers relative to said braking means, each of said rollers provided with a shaft having threaded off-set extensions in engagement with, and adapted to be secured against movement within said guide-ways, and means provided with said roller housing for facilitating lubrication of the rollers.

3. In a device of the class described, a bracket member having means for attaching it, a roller housing forming part of the bracket member and disposed symmetrically relative to the centre plane thereof, a pair of symmetrically arranged rollers mounted in said housing, and elongated roller guide means provided with and adapted to facilitate the adjustment of the rollers within said housing.

4. In a device of the class described, a bracket member having at one end an attaching hub provided with means for fastening it, the body 105 of the bracket member being off-set relative to said hub, a roller housing formed at the off-set other end of the bracket member and provided with symmetrically disposed roller guide means adapted to accommodate and to facilitate the adjustment of the axis of rollers, a pair of rollers mounted in and provided with means for fixing their position relative to said guide means.

5. In a device of the class described, a bracket member comprising an off-set body portion, an 115 attaching hub at one end thereof provided with means for fastening it in place, a roller housing at the other end of the body portion, two pairs of symmetrically disposed roller guide means arranged in said housing, a pair of rollers mounted 120 in said housing and provided with shafts adapted to register with said guide means, each roller shaft having provisions for facilitating the setting of the rollers, by means of their shafts, at desired positions within the housing.

6. In a device of the class described, as set forth in claim 3 and means provided with said roller housing for facilitating lubrication of the rollers.

THURSTEN ENGSTROM. 130
